UNITED STATES PATENT OFFICE.

NIELS C. ANDERSEN, OF CHICAGO, ILLINOIS, ASSIGNOR TO THE GOSS PRINTING PRESS COMPANY, OF CHICAGO, ILLINOIS, A CORPORATION OF ILLINOIS.

CYLINDER FOR PRINTING PRESSES.

Application filed January 29, 1926. Serial No. 84,740.

The present invention relates to collecting, folding, and delivery apparatus of rotary web perfecting presses, and more particularly to the construction and mode of operation of the collecting cylinder of a press of the aforesaid character.

In devices of the class to which my invention relates, a sheet or usually a plurality of sheets which will hereafter be called the web is first led onto and around the collecting cylinder, and a certain length is cut from it, which hereafter will be called a section. The leading end of this section is then brought into register with the leading end of the oncoming web, and the two are led forward together and adjacent to each other around the folding cylinder when a second section is cut from the web. The two sections are then folded together and delivered as the finished product.

If the trailing edge of the first section overlaps the cutting knife when the second section is cut, narrow strips of paper, which the pressmen call "sauerkraut" will be cut from the first section. This is undesirable and objectionable.

To meet this particular problem the structure shown in Evensen Patent No. 730,892 of June 16, 1903, was devised. The collecting cylinder which in this patent is also shown as a cutting cylinder, had a part of its periphery cut back to provide a recess or clearance into which the trailing end of the first section could be thrown at the time that the knife was projected to cut the second section from the web.

The growth in modern newspaper work now requires a press capable of collecting and folding a product varying in size from a few pages to sixty-four or more pages, and this demand has greatly complicated the problem of collecting.

While the clearance provided in the Evensen patent above mentioned for the trailing end of the section is essential to get a clean cut free of "sauerkraut", no matter what the thickness of the web may be, an appreciable increase in the thickness of the web requires a reduction in some manner in the diameter and the effective circumference of the cutting and collecting cylinder to secure proper folding and prevent chokes in the folding mechanism. If these alterations are made, and then thickness of the web is

materially reduced as is the case, the same difficulties arise from having the diameter and effective circumference of the cutting and collecting cylinder too small, all as hereafter explained.

To overcome these difficulties for webs of varying thickness, I reduce somewhat the diameter of the cutting and collecting cylinder itself, and reduce the effective length of its circumference. The effective length of its circumference I find can be reduced by increasing the recessed or relieved part of the cylinder, provided in the Evensen patent above mentioned, to form a longer depression. Then to compensate for different thicknesses of webs to be run through the machine, I provide adjustable means for filling out to varying degree the aforesaid depression in order to change the effective length of the circumference of the cylinder.

This means may be a plurality of fingers pivoted together to extend out of the body of the cylinder to fill out the depression, or it may be a plate likewise pivoted and capable of swinging out to varying degree to fill out the depression, or any other suitable means of equivalent effect.

Now, in order to acquaint those skilled in the art with the manner of constructing and using a device embodying my invention, I shall describe in connection with the accompanying drawings a machine employing my invention.

In the drawings:

Figures 1, 2 and 3 are diagrams, Fig. 1 showing the web held by the impaling pins on the cutting and collecting cylinder and being led onto said cylinder;

Fig. 2 shows the first section which is disposed on the cutting and collecting cylinder being severed from the web and the advance edges of both the web and the section being seized by the impaling pins of the folding cylinder;

Fig. 3 shows the trailing edge of the first section thrown into the relief or depression on the cutting cylinder in advance of the knife just before the second section is severed from the web;

Fig. 4 is a side elevational view of a cutting and collecting cylinder embodying my invention and showing the impaling pins and the adjustable means for filling out the cylinder;

Fig. 5 is a like side elevation taken from a point 90° from the viewpoint of Fig. 4;

Fig. 6 is a left hand end elevational view of the cylinder shown in Fig. 4;

Fig. 7 is a cross sectional view taken on the line 7—7 of Fig. 4;

Fig. 8 is an enlarged fragmentary elevational view of a modified form of the invention; and

Fig. 9 is an end view of the cylinder shown in Fig. 8.

Referring now to Figs. 1, 2 and 3, the folding cylinder 1 is provided with impaling pins 2 and 3, and with cutting slots 4 immediately in advance of the same. The cutting and collecting cylinder 5 is provided with impaling pins 6 and immediately in advance of the same a cutting knife 7 which plays through a suitable slot in the cylinder 5 and co-operates with the slots 4 for severing the sections from the web 8, which web is led down over a former 9 between the rollers 10 and 11. The mechanism for operating the impaling pins 2 and 3 forms no part of the invention and hence is not described in detail. The cylinder 1 is provided with rotary folding blades 12 and 13, which co-operate with the take-off folding rollers 14 and 15 as illustrated in Fig. 1.

As shown in Fig. 1, the leading edge of the web 8 is seized by the impaling pins 6 and is held upon the cutting and collecting cylinder 5 and drawn onto said latter cylinder. The cylinders 1 and 5 are geared together so that they always maintain a fixed relation with respect to each other. When the parts have moved forward to the point where the cutting knife again enters a slot 4, as shown in Fig. 2, the first section is severed from the web 8 and the impaling pins 6 drop back, releasing the forward edge of the first section. Simultaneously, the impaling pins 2 seize the advance edges of both the first section and the web and draw them onto the folding cylinder 1, as is shown in Fig. 3. When the continued motion of the parts again brings the knife 7 into register with the slot 4, the second section is severed from the web 8, and shortly thereafter both sections are pushed between the folding and delivery rollers 14 and 15, as indicated in Fig. 1. Just before the second cut is made, the trailing end of the first section is thrown down into a depression formed in the collecting and cutting cylinder just in advance of the knife 7, so that the trailing end of the first section or sheet will clear the knife 7. This action is facilitated by the whipping effect of drawing the first section about the outside of the folding cylinder 1.

When a very thick web is wound around the cylinder 5, the outer sheets particularly of this web lie in a position of an abnormally long circumference, and the cylinder 5, will, therefore, tend to pull them at a

speed greater than that of the normal web travel. Since the paper is inelastic, this excessive pull by the cylinder 5, causes the impaling pin 6 to pull out of the paper with the result that the leading end of the first section is not brought to register with the leading end of the oncoming web, but falls behind it. This lagging of the first section tends toward the cutting of "sauerkraut" as has been explained.

Furthermore, after the first section has been cut from the web as shown in Fig. 2, and this section together with the oncoming web have thereafter passed between the cylinder 1, and the cylinder 5, the slower speed of the web imposes a drag on the first section which tends to interrupt the control of the web and cause the folding mechanism to choke. Both these difficulties I overcome by reducing the effective circumference of the cutting and collecting cylinder.

I reduce the effective circumference of the cylinder 5, by forming a substantially extensive depression, the cylinder itself being slightly smaller in diameter so as to permit the maximum thickness of the web to be satisfactorily severed and collected. The recess or relief is indicated as 17 in Figs. 4 to 9 inclusive, and it extends from a point immediately in advance of the cutting knife 7 to substantially the end of the diameter passing through the knife or slightly short of the same.

This relief or cutting down is made sufficiently extensive and sufficiently deep to take up the full length of a page having a maximum web thickness without causing the trailing end to overhang the knife 7 and to be trimmed off to form the objectionable "sauerkraut".

If now a web of less thickness is to be collected, a corresponding increase in the effective circumference of the cylinder 5 must be made, otherwise this cylinder would draw the web at a speed less than normal, which would result in loss of control of the web and choking of the folding mechanism.

I provide means for increasing the effective circumference of the cylinder 5, this means being shown in detail in Figures 4 to 9 inclusive.

In the form shown in Figs. 4 to 7, inclusive, the cylinder 5 has a series of slots 18, 18 formed in the circumferential wall of the same at the forward end of the depression 17, and a series of plates or fingers 19 pivoted on the inner end of arms 20 by means of the shaft 21 are adapted to swing in and out of said slots 18 to a greater or less extent, as may be desired. The trailing edges 22 of these plates are depressed, so that they will not form a sharp shoulder even when the plates are swung to their outermost position. The extent of movement of the plates 19 is limited by a fixed

rod 23 extending through integral lugs 24 formed on the back sides of the fingers 19. A cover plate 25 is placed at each end of the cylinder 5, these cover plates being held by cap screws 26 which are threaded into the ends of the body of the cylinder 5 and which confine between them the shaft 21 upon which the fingers 19 are pivoted.

The fingers 19 are secured to the common shifter rod 23 by means of set screws 27 and the shifter rod 23 has the cap screws 28 threaded into the end of the same; these cap screws moving through slots 29 in the end plates 25 to permit of a common adjustment of the plates or fingers 19 simultaneously. It can now be seen that by releasing the cap screws 28 the plates or fingers 19 may be swung in common inwardly or outwardly with respect to the slots 18, so as to bring a greater or less extent of said plates up to the main periphery of the cylinder 5. By this means the effective length of the circumference of the cylinder 5 may be varied without interfering with the portion of the recess or depression immediately in advance of the knife 7.

While I have shown the adjustment plates or fingers as being disposed in the forward part of the continuous depression 17, it is to be understood that a depression might be formed upon another part of the periphery of the cylinder 5, and its extent varied by like means without departing from my invention.

Also, instead of having a series of fingers or plates 19 extending through the slots 18, a continuous or overhanging plate, such as shown at 30 in Fig. 8, might be employed, either in connection with a part of the depression 17 or a separate depression, as may be desired. As shown in Figs. 8 and 9 a longitudinal recess 31 is formed in the bottom of the depression 17 adjacent its leading edge 32, and in this longitudinal recess a curved plate 30 is seated, this plate having at its ends pivot lugs 33 pivoted on cap screws 34 which are threaded through plates 35 secured upon the ends of the cylinder 5. The plates 35 are secured upon the ends of the cylinder 5 by the machine screws 36 which have counter sunk heads and the shanks of which are threaded into the main body of the cylinder. The opposite ends of the end plates 35 are secured by like machine screws 37 having counter sunk heads and shanks likewise threaded into the main body of the cylinder. The longitudinal adjusting plates 30 have slotted lugs 38 with adjustable cap screws 39 passing through the slots and threaded into the plates 35 to clamp the slotted lugs in any desired position. Thus, by loosening the cap screws 39 and swinging the adjustable plate 30 about the pivot 34, the effective circumferential length of the

cylinder may be changed by moving the plate 30 in or out to a greater or less degree and then clamping the same by means of the clamping screws 39.

Attention is called to the fact that whereas in the form shown in Figs. 4 to 7, inclusive, the trailing edge of the adjusting means moves in and out, in the form shown in Figs. 8 and 9 the leading edge of the adjusting means 30 is swung in and out. Either method may be employed regard being had to the space and material requirements of the particular installation.

It may now be seen that my invention provides a cylinder which is adjustable in circumferential length without interfering with the arc of the depression which receives the trailing edge of the first section or sheet, so that assuming that the proper length of circumference of the cylinder has been provided, the trailing edge of the first section or sheet will be permitted to be thrown into the depression or recess to prevent the same being again cut by the knife 7.

It will also be seen that by changing the effective circumference of the cylinder provision is made for handling sheets or sections cut from webs of different thickness.

By my invention it is possible to make the cylinder considerably under size to take care of large products because I can bring out the circumference to any size, within limits, for proper operation with a smaller product.

I do not intend to be limited to the details shown and described.

I claim:—

1. A collecting cylinder having a portion of its periphery depressed, the depressed portion being arranged to receive the rear end of the web, and adjustable means mounted on said cylinder for filling out a portion of said depression to accommodate the cylinder to various thicknesses of web.

2. A cutting and collecting cylinder having a cutting blade, a portion of the periphery of said cylinder adjacent to and in advance of the cutting blade being depressed to receive the rear end of the web, and adjustable means pivoted on the axis parallel to the axis of the cylinder for filling a portion of said depression.

3. A collecting cylinder having means for holding the advance edge of a web, a portion of the periphery in advance of said holding means being depressed to receive the rear end of the web, and adjustable means on the cylinder for filling the advance portion of said depression to a desired degree.

4. A cutting and collecting cylinder having a cutting blade and means for holding the advance edge of a web, said cylinder having a portion of the periphery thereof cut down to a smaller effective diameter to change the effective circumferential length

of the cylinder, and adjustable means for filling out a portion of said cut down part of the cylinder for adjusting the cylinder to different thicknesses of web.

5. In a cylinder of the class described, a cutting knife, impaling pins behind said knife, and means for adjusting the effective circumferential length of the cylinder, said means being adapted to be moved out laterally of the cylinder.

10. 6. A cutting and collecting cylinder having a cutting blade and impaling pins, and means for varying the effective circumferential length of the cylinder, comprising a plate pivoted on an axis parallel to the longitudinal axis of the cylinder, said plate being adapted to be projected laterally from the surface of the cylinder.

15. 7. In a collecting cylinder of the class described, means comprising a part of the circumferential surface of the cylinder for

adjusting its circumferential length to adapt it to different thicknesses of web.

8. A collecting cylinder having a peripheral speed lower than the surface speed of 25 the web with which it cooperates and having mechanical means comprising a part of the cylinder for increasing the circumference of the cylinder to increase the peripheral speed. 30

9. In combination, web forwarding means and a collecting cylinder for receiving the web, said cylinder having a peripheral speed lower than the speed of the web, and means forming a part of the periphery of 35 the cylinder for increasing the effective circumference of the cylinder to adjust it to the speed of the web.

In witness whereof, I hereunto subscribe my name this 25th day of January, 1926.

NIELS C. ANDERSEN.
